SAMUEL OLSON & COMPANY INC., OF CHICAGO, ILLINOIS, A CORPORATION OF
ILLINOIS

REFUSE CHUTE

Application filed March 14, 1929. Serial No. 346,884.

This invention relates to refuse chutes of the general type used in connection with various building structures, such as hospitals, hotels, apartments, office buildings, etc., wherein the chute is designed for access at one or more floor levels; and more particularly the invention resides in the provision of an improved form of closure for the several floor level openings.

10 A primary object of this invention is to produce an improved closure adapted to substantially isolate the discharging of refuse into the chute at each opening from all the others, so as to prevent back drafts, odors, 15 dust, etc. from entering the building, and also reducing fire hazards, in guarding against transmission of fire from one floor to another through the chute. A further object is to provide a closure adapted when operated to substantially close the chute passage-way both above and below the floor level opening. Another object is to provide an improved closure that is simple, positive and durable, and which, when inoperative, permits unhampered passage of refuse through 20 the chute from above. It is also an object to produce a chute construction including a closure wherein there is no extension or projection into the interior of the building, thus 25 obviating unsightly appearance as well as affording use of the full floor space adjacent the chute opening. The invention consists in certain features and elements of construction, herein shown and described as indicated in the claims.

In the drawings:

Figure 1 is a longitudinal sectional view of a refuse chute embodying the present invention; the closure apparatus being shown in position to afford access to the chute from the interior of the building.

Figure 2 is a fragmentary transverse sectional view taken at line 2—2 on Fig. 1.

45 Figure 3 is a view similar to Fig. 1, showing a modified construction.

Figure 4 is a transverse sectional view taken at line 4—4 on Fig. 3.

50 Figure 5 is a fragmentary view of a modified closure operating mechanism.

Figure 6 is a longitudinal sectional view of a further modified construction; and

Figure 7 is a transverse section taken substantially as indicated at line 7—7 on Fig. 6.

Figure 8 is a partly diagrammatic view of 55 the nature of a vertical section of a building having several floor levels and equipped with a chute embodying this invention extending through the several floors.

For the purpose of illustration our invention is shown in connection with an upwardly extending chute, 10, built onto the exterior of a building wall, 11, it being understood that if desired, this chute could be a permanently walled or built-in structure of the 60 building. As shown, the chute is of steel plate construction, rendering it fire proof, and is of three wall formation using the building wall to complete it. Generally in chutes of this character provision is made for 65 discharging into the chute at several places, and for this purpose suitable openings, 13, are formed in the building wall 11, preferably in convenient relation to the floor levels, as indicated at 14. Mounted adjacent each wall 70 opening is my improved closure apparatus comprising a pair of doors, 16 and 17, hinged- 75 ly supported on parallel horizontal axes and mounted in vertically spaced relation at the front and rear walls of the chute. These 80 doors are preferably of plate and angle construction to render them light weight, and are mounted on transversely extending hinge shafts, 18 and 19, respectively.

85 The ends of the shafts 18 of the upper door 16 are journaled in bearings, 20, secured to the side walls 21 of the opening 13 adjacent the top thereof a distance inwardly of the outer side of wall 11, so as to permit said door to swing downwardly into vertical position (as indicated in dotted lines) to substantially close said opening; in such position the door 16 hangs at one side of the effective passage-way of the chute. The ends of pivot shaft 19 of the lower door are journaled in bearing brackets 22 secured to the chute side wall at a substantial distance below the opening 13 and at a laterally offset portion 23 of the chute back wall. Thus, when the lower door 90 is permitted to assume the vertical down- 95

wardly extending position (as indicated in dotted lines) it too hangs to the side of the effective chute passageway. The bearing brackets 22 are preferably of the upwardly open socket type, as shown in Fig. 2, so as to facilitate the assembly or replacement of this door.

The upper and lower doors are connected for conjoint actuation, and are adapted to be simultaneously swung to extend transversely of the chute, as shown in the drawings, and supported in such position. These doors are designed so that in such transverse position they substantially occupy the cross sectional area of the chute, substantially closing the chute opening both above and below the chute opening. The interconnection of the doors consists of a pair of laterally spaced cables, 24, pivotally secured at their upper ends to the outer end of the door 16, and at their lower ends to the top of the lower door 17 adjacent the sides of the doors, so that said cables are positioned relatively close to the chute side walls, to avoid the obstruction of refuse from above when the doors are lowered into inoperative position.

The lower or inner face of the upper door 16 is provided with a plurality of projecting lugs, 26, connected by a rod, 27, forming a convenient hand grip whereby said upper door may be pushed upwardly about its pivot axis transversely of the chute, and due to the cables 24 the lower door 17 is simultaneously swung upwardly in transverse position below the opening 13. A spring catch, 28, is secured to the back wall of the chute, and is adapted to engage said upper door 16 when it is swung upwardly, for supporting said doors in such transverse position. Secured to said catch is an operating rod, 29, positioned above the opening and having its opposite end slidably supported in the reinforcing liner, 30, of said opening 13; the extreme end of said rod 29 extending slightly beyond the liner 30 and adapted to be engaged by the inner door 31 which serves to complete the closure on the inside of the wall 11. It will now be seen that when door 31 is closed, the doors 16 and 17 hang in vertical position as indicated in dotted lines, and as soon as door 31 is opened, spring catch 28 is permitted to assume operative position to engage and support the doors when the upper door is pushed upwardly. In such position, the upper side of the lower door 17 acts as a false bottom to receive the refuse through the opening 13 and to discharge it into the chute when the inner door 31 is closed; the closing of said door 31 engages the end of rod 29 thus shifting the catch 28 to permit both of said doors 16 and 17 to drop under the influence of gravity.

In this arrangement the inner door 31 is practically closed before the refuse actually is discharged. This general construction is particularly advantageous in that the interior

of the building may be kept neat appearing without unsightly receiving hoppers projecting into the rooms or halls, while permitting the full use of the floor area adjacent each opening. In the event that refuse is discharged down the chute from above, while the doors 16 and 17 of a closure at a lower level are positioned across the chute, the top of the upper door 16 serves as a false bottom to catch the refuse from above, which will be discharged down the chute when the doors 16 and 17 at this particular level are shifted to release the refuse loaded in at this level.

Figs. 3 and 4 illustrate a modified construction which is a refinement with respect to the actuation of the cooperating doors 16 and 17. The construction and connection of the doors is substantially the same as in Fig. 1, except that the pivot shaft, 18^a, of the upper door 16 is rigidly connected for rotation therewith by reason of the shaft being of square cross section; the ends of the shaft are turned round and journaled in bearings 35 secured to the wall 21 of the opening 13. One end of said shaft extends through the wall 21 into an opening 36 formed in the wall 11, adjacent opening 13. Rigidly secured to the projecting end of said shaft is a lever arm, 38, which extends in the plane of the upper door 16 and has pivoted to its outer end a link, 39, whose other end is pivoted to the end of operating lever 40 which is fixedly pivoted at 41 to the wall 42 of the opening 36. The outer end of the lever 40 is formed with a handle, 43, for swinging the lever about its pivot 41; thus swinging the upper door 16 upwardly to transverse position which action simultaneously raises the lower door 17 across the chute. The doors are supported in such position by reason of the pivotal connection of the link 39 and lever 40 being swung to a position beyond the plane of the pivots 41 and pivot connection of link 39 with arm 38; and the movement is limited against buckling by the handle 43 engaging the lower sill of opening 36.

An inside door 44 is provided to complete the closure of opening 36 from the interior of the building. Thus, the doors 16 and 17 may be operated independently of the opening or closing of door 31; this is of particular advantage in that after the refuse is deposited on lower door 17, the door 31 may be closed and the doors 16 and 17 then operated to discharge the refuse downwardly in the chute, avoiding any possibility of back draft, or refuse being blown back in the building through the main opening 13.

Fig. 5 shows a modified construction for operating the doors 16 and 17. Rigidly secured on the end of square shaft 18^a, extending into the opening 36, is a worm gear 46 operatively meshed with a worm 47 mounted on an operating shaft 48 journaled in bearings 49 secured to the wall 21. The end of

the shaft 48 is formed with a suitable crank-engaging portion 50 which extends through a fixed escutcheon plate 51 forming the closure of the opening 36 on the inside of the building. It will be apparent that with this form of operating mechanism, the doors 16 and 17 may be actuated and will be held in any position by reason of the locking effect of the pitch of the worm and gear.

10 Figures 6 and 7 represent a further modification which is, in general, similar to the construction shown in Figs. 3 and 4. In this arrangement the square hinge shaft, 18^b, of the upper door, 16, is reduced at its ends and 15 journaled in bearings, 35, secured to the walls, 21; an end of said shaft extending through the wall, 21, into the opening, 36, adjacent the main opening, 13. Rigidly secured to the projecting end of said shaft is a 20 sheave, 55, to which is anchored the end of the operating chain, 56, which is trained over a pair of vertically spaced idler sheaves, 57 and 58, and thence downwardly and having its other end fastened to a sheave, 59, fixed 25 on the projecting end of the square hinge shaft, 19^b, of the lower door, 17; said shaft, 19^b, having its ends reduced and journaled in bearings, 60 secured to the casing, 10. The 30 sheaves, 57 and 58, are freely journaled on stud brackets, 61 and 62, respectively, secured to the outside of casing, 10. The chain intermediate sheaves, 57 and 58, is of excess length and is extended forwardly in doubled 35 relation and connected to a turnbuckle, 63, which in turn is pivotally connected to one 40 end of a link, 64, the other end of which link is pivoted at 65, to a bell crank, 66, which is mounted on a fixed pivot, 67, on the wall, 21. The bell crank is formed with a long arm 45 66^a, which serves as a convenient hand lever for operating the doors.

Thus, in pulling the lever, 66^a, downwardly from the position indicated at "A" about its pivot, 67, the chain intermediate the sheaves, 57 and 58, is drawn toward the building, causing the chain wrapped on the sheaves, 55 and 59, to be paid out, rotating the shafts, 18^b and 19^b, for swinging the doors, 16 and 17, upwardly to extend transversely of the chute, 10, both above and below the main opening, 13. It will be seen that in this position of the doors the lever, 66^a, is swung down against the wall, 11, with the pivot, 65, positioned below the fixed pivot, 67, thus acting 55 to lock the mechanism for maintaining the doors in chute closing position. By swinging lever, 66^a, upwardly, moving its pivot, 65, above pivot, 67, the doors, 16 and 17, are permitted to fall by gravity, and in so doing 60 wrap the chain, 56, a portion of a turn about their respective sheaves, 55 and 59.

We claim:

1. A chute having a lateral opening, a pair of swinging doors, one of which normally closes said opening, said doors being

hingedly mounted in vertically spaced relation adjacent the opening and adapted to be swung transversely of the chute for substantially closing the passageway thereof both above and below said opening, and means for supporting said doors in such position.

2. A chute having a lateral opening, a pair of co-operating doors hingedly mounted on vertically spaced axes, one of said doors normally closing the opening, means interconnecting the doors for conjoint actuation, said doors being adapted to be swung about their axes, transversely of the chute for substantially closing the passageway thereof both above and below said opening respectively, and means for maintaining said doors in such position.

3. In the combination defined in claim 2, means operatively connected to one of the doors for moving both of them into and out of their transverse positions.

4. In the combination defined in claim 2, each of said doors being supported to hang normally in a substantially vertical plane at one side of the effective passageway of the chute.

5. A chute having a lateral opening, an upper door hingedly mounted adjacent the top of the opening, and normally closing the same, and movable to extend transversely of the chute to substantially close the passageway above said opening, a lower door hingedly mounted below said opening and movable transversely of the chute for substantially closing the passageway below the opening, and means for supporting said doors in such chute-closing position.

6. A chute having a lateral opening, an upper door hingedly mounted adjacent the top of the opening and adapted to normally close the same, a lower door hingedly mounted below said opening, and means for swinging said doors about their axes transversely of the chute for substantially closing the passageway above and below said opening respectively.

7. In the combination defined in claim 6, said means being also adapted to maintain said doors in chute-closing position.

8. In the combination defined in claim 6, said lower door being hingedly mounted in said chute at the side opposite said opening.

9. A chute having a lateral opening, an upper door hingedly mounted adjacent the top of the opening and normally closing the same, a lower door hingedly mounted below the opening at the side of the chute opposite said opening, means connecting said doors for conjoint actuation, and means operably connected to the upper door for swinging both said doors transversely of the chute to substantially close the passageway thereof both above and below said opening, said

means maintaining said doors automatically in such position.

10. In combination with a chute having a lateral opening, two vertically spaced doors, operating means and separate connections from said means to the respective doors for shifting said doors simultaneously to extend transversely of the chute for substantially closing the passageway thereof both above and below the lateral opening.

11. In combination with a building wall, a chute adjacent the wall, said chute and wall having a set of registered openings, a pair of cooperating doors hingedly mounted adjacent the openings, one of said doors normally closing said openings, means interconnecting said doors for conjoint actuation, said doors being adapted to be swung upwardly about their hinge axes to positions substantially closing the passageway of the chute both above and below said registered openings, detent means for maintaining said doors in such position, a door mounted on the inner side of the wall for closing the opening, and means responsive to the closing of said last mentioned door for releasing said detent means, permitting said connected doors to return to normal position.

12. In combination with a wall of a building, an upwardly extending chute adjacent the wall, said chute and wall having a plurality of vertically spaced openings to afford access to the chute from the inner side of the wall, two vertically spaced doors adjacent each opening, means interconnecting each set of doors for conjoint actuation and means for positioning each set of doors transversely of the chute for substantially closing the passageway thereof both above and below the opening.

13. A chute having a lateral opening, two movable doors and means for shifting said doors to extend transversely of the chute for substantially closing the passageway thereof both above and below said lateral opening.

14. A chute having a lateral opening, two vertically spaced doors, means interconnecting said doors for conjoint actuation and means for placing said doors transversely of the chute for closing the passageway thereof both above and below said lateral opening.

15. A chute having a lateral opening, two vertically spaced doors, means interconnecting said doors for conjoint actuation and means operatively connected to one of the doors for moving both of them to extend transversely of the chute for substantially closing the passageway thereof both above and below said lateral opening.

16. In combination with a wall of a building, a chute disposed adjacent the wall, said wall and chute having a lateral opening connecting the interior of the building with the chute, two interconnected movable doors, means for positioning said doors transversely

of the chute for substantially closing the passageway thereof both above and below the lateral opening and an inner door for closing said opening.

17. In combination with a wall of a building, an upwardly extending chute adjacent the wall, said chute and wall having an opening to permit access to the chute from the opposite side of the wall, a swinging door mounted on a horizontal axis normally closing the opening at the side adjacent the chute, and adapted to be swung transversely of the chute passageway for effectively closing the same above the opening, detent means engageable by said door for holding it in such transverse position, a second door for closing said opening in the wall from the opposite side thereof independently of said swinging door, and means actuated by said second door when it is moved to closed position for releasing said detent means and permitting the first mentioned door to swing to closed position.
